UNITED STATES PATENT OFFICE.

FRANK ANDRUSZKIEWICZ, OF EASTHAMPTON, MASSACHUSETTS.

SLED.

1,110,525.

Specification of Letters Patent. Patented Sept. 15, 1914.

Application filed March 30, 1914. Serial No. 828,292.

To all whom it may concern:

Be it known that I, FRANK ANDRUSZKIEWICZ, a citizen of the United States, residing at Easthampton, in the county of Hampshire and State of Massachusetts, have invented certain new and useful Improvements in Sleds; and I do declare the following to be a full, clear, and exact description of the invention, such as will enable others skilled in the art to which it appertains to make and use the same.

This invention relates to new and useful improvements in sleds and the primary object of the invention is to provide a sled for children's use constructed of a single strand of metal.

A further object of the invention resides in providing a device which by being constructed of a single strand of metal is capable of more resiliency and greater strength than those now in use.

Still another object of the invention resides in providing a sled which is simple in construction, inexpensive to manufacture, and one which is extremely efficient in use.

With these and other objects in view, my invention consists in the novel features of construction, combination and arrangement of parts, as will be hereinafter referred to and more particularly pointed out in the specification and claims.

In the accompanying drawings forming a part of this application: Figure 1 is a perspective view of a sled constructed in accordance with my invention; Fig. 2 is a transverse section therethrough; Fig. 3 is a plan view of a slightly modified form of the invention; Fig. 4 is a side elevation thereof; Fig. 5 is a transverse section therethrough as seen on line 5—5 of Fig. 3; Fig. 6 is a plan view of a further modified form of the invention; Fig. 7 is a transverse section therethrough as seen on line 7—7 of Fig. 6, looking in the direction of the arrows; Fig. 8 is a side elevation of this form of the device; and Fig. 9 is a perspective view of a still further modified form of the invention.

In describing the invention, I shall refer to the drawings in which similar reference characters designate corresponding parts throughout the several views, and in which 1 indicates a sled constructed of a single strand of heavy wire 2, the same being looped intermediate of its ends and bent to form the rear transverse bar 3 of the device.

That portion of the wire continuing from the rear bar 3 is bent downwardly to form the vertical rear supporting portions 4 and continuing from these portions, the wire is bent rearwardly and thence forwardly as indicated at 5, the forwardly bent portions continuing for considerable length to form the runners proper, and indicated as 6. The portions of the wire continuing from the forward ends of the runners are bent upwardly in the usual manner and then inwardly as shown at 7, the portions being then intertwined and disposed rearwardly, such engagement being shown at 8. This intertwining of the portions and the extension thereof rearwardly, continues for a short distance and the portions of the wire are then separated and disposed outwardly in opposite directions, the forward portions being again bent and extended rearwardly to form the top rails 9 of the sled. The extreme rear ends of the portions forming the top rails are engaged with the rear transverse bar 3 by being wrapped therearound, and this completes the formation of the sled. The top rails, together with the rear transverse bar and the connection 8 which affords a bracing means between the top rails and the forward portions of the runners, completes the upper portion of the sled proper, and if desired, a supporting board or seat may be applied thereto. However, no such board is absolutely necessary if the sled be made small enough to admit of one sitting or lying thereon.

In Figs. 3, 4 and 5, I have shown a slightly modified form of the invention wherein a strand of heavy wire is first bent and looped intermediate of its ends to form the rear transverse bar 10. The portions of the wire continuing from the rear bar depend therefrom to provide vertical rear supporting portions 11 and the wire is then bent rearwardly and forwardly, as indicated at 13, thus positioning the rear upper bar 10 in a plane forward of the plane of the extreme rear ends of the runners. The portions of the wire continuing from these rearward and forward bent portions 12 extend forwardly for a considerable distance whereby to provide runners 13. The forward ends of the runners are bent upwardly as shown at 14 and the extreme upper ends thereof are looped and twisted to provide eyes 15 whereby flexible connections or the like may be engaged therewith for the

propulsion of the sled. The portions of the wire continuing from the eyes 15, are disposed inwardly toward one another and then intertwined. This intertwined portion 5 extends rearwardly for a short distance as shown at 16 and the portions are then again separated and bent outwardly in opposite directions as indicated at 17. These portions of the wire indicated as 17 are disposed 10 outwardly to planes adjacent the planes of the runners and are then bent rearwardly to form the top rails 18. These portions of the wire forming the top rails are wrapped around the rear upper bar 10 and are then continued forwardly in the space 15 between said top rails as indicated at 19. The extreme forward ends of these portions 19 are then engaged with the outwardly disposed portions 17 which completes the formation of the sled. This form of sled is 20 substantially the same as the first mentioned form, the same being provided in addition with means for the engagement of a drawing cord or chain; and also with additional 25 means for strengthening the upper portion of the sled. It will be noted that the upper rear transverse bar and the portions indicated as 17, 18 and 19 form the top of the sled proper upon which a seat may be applied, if desired. 30

In Figs. 6, 7 and 8, I have shown a still further modified form of the invention wherein a strand of heavy wire is first bent and looped intermediate of its ends to form 35 a forward or front transverse bar 20, the ends thereof being looped and twisted to form eyes or engaging members 21. The portions of the wire continuing from these eyes at the ends of the bar 20 are extended 40 downwardly and bent rearwardly to form forward portions 22 or runners for the sled, these forward portions forming the front or forward halves of the runners. The wires continuing from these forward portions of 45 the runners are bent upwardly and inwardly, the inwardly bent portions being wrapped about one another as clearly shown in the drawing to form an intermediate transverse bar 23. The sections of the wire, after being 50 intertwined as shown and set forth, are bent and continued rearwardly to form the rear portions or halves 24 of the runners proper of the sled. The extreme rear ends of the runners are bent upwardly and inwardly as indicated at 25 similar to the showing made in connection with the previously described forms and the sections of the wire continuing from these portions 55 are again bent upwardly and inwardly, said inwardly extending portions being intertwined as clearly shown to provide a rear transverse bar 26. The one section of the wire continuing from the rear bar 26 which is formed by the intertwining of the sections 60 of the wire, is continued forwardly and

looped about the intermediate transverse bar 23, the same then continuing forwardly and being bent inwardly. The inwardly bent portion is looped about the forward transverse bar 20 and twisted as indicated at 28. 70 This section of the wire continuing from the twisted portion is then bent outwardly and rearwardly and finally engaged with the intermediate transverse bar 23 adjacent the opposite end thereof. The other section of 75 the wire continuing from the transverse rear bar 26 is merely continued forwardly and engaged directly with the transverse intermediate bar 23 at a point indicated at 29. The portions of the wire which continue 80 from the transverse rear bar and which are engaged with the intermediate transverse bar and the forward transverse bar form the top rails or upper bars for the sled and afford means whereby a seat may be applied 85 if desired. The same also considerably strengthens the parts of the device, as appears obvious.

In Fig. 9, I have shown still another modified form of the invention wherein a heavy strand of wire is first bent and looped intermediate of its ends to form a forward transverse bar 30 and the wire forming this bar 30 is looped and twisted so as to provide 90 engaging eyes 31 at the ends of said bar. Continuing from these engaging eyes, the sections of the wire are bent downwardly and rearwardly to form the forward halves 32 of the runners of my improved sled. The sections of the wire continuing from 95 these forward halves 32 are first bent upwardly to form the vertical side bars or rails 33, the latter also forming handle members as will be hereinafter and more particularly set forth. The sections of the wire are looped or bent and then twisted about the upper portions of these side bars 33, such twisting continuing for the length of the upper halves of said bars 33. The sections of the wire are then directed transversely across the sled in planes on opposite sides of the bars 33, said transversely directed portions being so spaced from one another as to substantially provide a seat 100 34. The wires continuing from this formation, are engaged with the adjacent side bars 33 and twisted therearound for the lower halves thereof. Continuing from these bars 33, the twisted wires are bent and extended 105 in the same longitudinal planes with the forward halves 32 of the runners to form the rearward halves 35 thereof, thus completing the formation of said runners proper. The wires forming the rear halves 35 of the runners are bent upwardly and 110 forwardly as shown at 36 in a manner similar to such bent portions disclosed and described in the previously mentioned forms. The wires continuing from these portions 36 are then bent upwardly to form the rear 115

vertical side bars 37 and the wires forming these bars are then looped, twisted and bent as described in connection with the first mentioned vertical side bars, thus providing 5 a rear seat 38. The wires continuing from the seat formed at the rear of the device, after being looped around the lower portions of the vertical side bars 37 are continued forwardly to form the top rails 39, 10 these top rails being engaged with certain wraps of the wires of the first mentioned vertical side bars 33 and the extreme forward ends of the wires forming these top rails are finally engaged with the portions 15 of the wire forming the engaging eyes 31. The complete sled is thus formed of a single strand of wire, the same being provided with seats and the upper extensions of the vertical side bars are designed to form handles or the like for the seats thus formed. 20

From the foregoing, it will be seen that I have provided a simple, inexpensive, and efficient means for carrying out the objects of the invention, and while I have particularly described the elements best adapted to 25 perform the functions set forth, it is obvious that various changes in form, proportion and in the minor details of construction, may be resorted to without departing from 30 the spirit or sacrificing any of the principles of the invention.

Having thus described my invention, what I claim is:

1. A sled formed of a single strand of 35 metal bent to include runners, a transverse member continuing from the rear portions of said runners, and top rails formed also from continuations of the runners and engaged with the transverse member.

40 2. A sled formed of a single strand of metal designed to form runners, a transverse

bar continuing from the rear portions of said runners, the forward portions of the runners being bent upwardly and thence inwardly and intertwined, the intertwined 45 portion being extended rearwardly and the sections of the wire then spread and continued rearwardly to form top rails for the device.

3. A sled formed of a single strand of 50 metal bent to form an upper transverse bar, the portions of the metal continuing from said bar being bent downwardly and then forwardly to form runners, the portions of the metal continuing from the forward ends 55 of said runners being bent upwardly and inwardly and then intertwined to extend rearwardly, the portion of the metal being then spread outwardly and bent rearwardly 60 for engagement with the rear transverse bar, whereby to form top rails for the sled.

4. A sled formed of a single strand of metal bent to form an upper transverse bar, the portions of the metal continuing from said bar being bent downwardly, rearwardly 65 and thence forwardly to form runners, the portions of the metal continuing from the forward ends of the runners being bent upwardly and inwardly for engagement with one another whereby to form a forward 70 transverse connection, the portions continuing from the last mentioned connection being spread and continued rearwardly to form top rails, said top rails having engagement with the rear transverse bar. 75

In testimony whereof I have hereunto set my hand in presence of two subscribing witnesses.

FRANK ANDRUSZKIEWICZ.
